United States Patent Office

Des. 181,367
Patented Nov. 5, 1957

181,367

WASH MITTEN

Rolf Moroni, New York, N. Y., assignor to American Collo Corporation, New York, N. Y., a corporation of New York

Application August 30, 1954, Serial No. 32,077

Term of patent 3½ years

(Cl. D9—2)

FIG. 1.

FIG. 2.

FIG. 3.

Fig. 1 is a front elevational view of the wash mitten, showing my new design;

Fig. 2 is a side elevational view thereof;

Fig. 3 is a plan view of one end thereof; and

Fig. 4 is a plan view of the other end thereof.

I claim:

The ornamental design for a wash mitten, as shown.
